UNITED STATES PATENT OFFICE.

CLARENCE S. APPLAS, OF SACRAMENTO, CALIFORNIA.

HOLDER FOR AUTOMOBILE REGISTRATION CARDS.

Application filed May 9, 1925. Serial No. 29,133.

To all whom it may concern:

Be it known that I, CLARENCE S. APPLAS, a citizen of the United States, residing at Sacramento, in the county of Sacramento and

5 State of California, have invented new and useful Improvements in Holders for Automobile Registration Cards, of which the following is a specification.

This invention relates to holders for automobile registration or license cards.

10 The object is to provide a simple and cheaply manufactured device for holding an automobile registration card or a driver's license card in a position on the steering post of an automobile to be readily inspected by an officer of the law, such open and constant display of said cards being required in many States in order that there may be obtained certain required facts regarding

15 the car and the driver without undue loss of time.

Another object is to provide a holder for this purpose of flexible and water proof material which is adapted to readily receive 25 the card within the pocket comprising the body member and displaying the printed information thereon through a water-proof, transparent front panel or wall, said card being fully protected from dirt or moisture

30 when the holder is bent or wrapped around the steering post, and frictionally held on the same by binding or lacing means connecting the ends of the holder, which enables the device to be applied to different sized posts.

A full and complete understanding of the invention may be obtained from a consideration of the following detailed description, taken in connection with the accompanying 40 drawing forming a part of this specification, it being understood that while the drawing shows a practical form of the invention, the latter is not to be confined to strict conformity therewith, but may be changed or modified, so long as such changes or modifications mark no material departure from the salient features of the invention, as 45 specifically pointed out in the appended claims.

50 In the drawing, in which similar reference characters designate corresponding parts throughout the several figures:—

Figure 1 is a side elevation showing the invention as applied to the steering post of an automobile.

Figure 2 is a side elevation of the device in applied position and looking from the opposite side to show the means for holding the same in position.

Figure 3 is a plan view of the back of 60 the holder in open position as when introducing a card prior to application to the steering post.

Figure 4 is a horizontal sectional view 65 through Figure 3.

Various devices have been used for holding registration or license cards in automobiles and displaying the same in full view at all times, in accordance with the legal requirements in many localities, but 70 said devices require that they be either screwed or clamped to the dash, where they are more or less in the way and result in marring or defacing the dash or other part to which they may be attached. The present device may be firmly held to the steering post below the steering wheel so as not to interfere in the slightest with the operator, and where it may not be accidentally 75 dislodged or damaged, and at the same time readily turned toward the left or driver's side of the car to be easily inspected by an officer or other person standing at the side.

The invention comprises a rectangular 80 body member 1 formed of thin, flexible leather or some other suitable water-proof material having flexible qualities and of a length sufficient, when formed in a manner to be described, to reach substantially around the maximum-sized post.

The end portions of the body member are turned back against the front side thereof, as indicated at 2 to provide overhanging portions to house the ends of the registration or other card, and the upper and lower 95 marginal portions of the body member are folded over on the front side thereof also, as indicated at 3 to house the upper and lower edges of said card. The turned over portions 2 and 3 are adapted to receive the 100 edges of a rectangular front panel or wall 5 which is formed of material such as celluloid which is clearly transparent, flexible and water-proof for protecting the registration or other card from dirt or moisture. The turned portions 2 and 3, as well as the 105 margins of the transparent front wall 5 and the back of the holder 1 are then stitched a short distance from the free inner edges of said portions, as shown at 4, which thus 110

provides a continuous overhanging flange to completely surround the edges of the card.

Adjacent to the stitches 4 at one end of the body member, the back wall 1 is provided with a vertically disposed slit 6, extending the full width or height of the pocket, and the registration or other card, indicated at 7 in Figure 3 of the drawing, is adapted to be introduced into the pocket thus formed through said slit 6, the body member 1 forming a complete cover for the back of the card, and the transparent front wall completely covering the front of the card and permitting ready inspection of the same.

The turned back portions 2 at the ends of the body member are somewhat wider than the turned portions at the top and bottom, and are adapted to have hooks or eyelets 8 secured in a vertical line thereon, the clinching portions 9 of the same passing through both layers and located at the rear or inner side of the device.

The hooks 8 of each series are regularly spaced apart and opposite to each other when the holder is bent into a cylinder as when in use, and the holder is preferably held in close frictional engagement by means of a thin, strong and flexible wire 10, having one end preferably connected to the lowermost hook 8 at one side, as indicated at 11, the free portion of said wire being interlaced in the several hooks, as clearly shown in Figure 2 of the drawing. By lacing the device in the manner shown, the terminal portion of the wire may be twisted about the other terminal portion of the wire at the point of fastening, as shown at 12 in said figure, and it will be seen that a uniform strain is put on the hooks transversely of the gap between the ends 2-2 to cause the holder, together with the card therein, to lie closely and uniformly against the steering post 13, whereon the reading matter on the card 7 may be readily brought in view, if necessary for an inspection, by simply turning the holder, the frictional engagement be-

ing sufficient to prevent the device from slipping down on the said post.

From the foregoing it will be seen that a simple, easily applied, cheaply manufactured, and strong and durable holder has been provided for holding registration or other cards on the steering posts of automobiles in a manner to constantly display the reading matter thereon, and to protect the same from dirt and moisture.

What is claimed is:—

1. A holder for automobile registration cards comprising a rectangular body member formed of flexible protective material, said body member having its marginal portions turned over on the front, a flexible transparent sheet stitched around its margins within said overturned portions to form a pocket, said body member having a slit adjacent to one end to form an entrance opening to said pocket for the introduction of a registration or other card, and spaced hooks secured to the front face of the overturned ends of the body and adapted to receive a lacing to support the holder around an automobile steering post in a manner to display the said card.

2. A holder for automobile registration or license cards comprising a rectangular pocket formed of leather or other waterproof material and adapted to be bent and wrapped around an automobile steering post, said pocket having a transverse slit in the rear wall adjacent to one end of the same for introducing said card therein, and having a flexible transparent front wall to display the card, opposed series of spaced hooks attached to the front of the holder and adjacent to the ends of the same, and a wire lacing secured to one terminal hook and adapted to be interlaced in the hooks and secured to hold the device in tight frictional engagement around said steering post for displaying said card.

In testimony, that I claim the foregoing as my own, I have hereto affixed my signature.

CLARENCE S. APPLAS.
